HERBERT PLATT, OF CUMBERLAND, MARYLAND, AND NATHANIEL C. SHANE, JR., OF PATERSON, NEW JERSEY, ASSIGNORS TO CELANESE CORPORATION OF AMERICA, A CORPORATION OF DELAWARE

APPARATUS FOR TREATING FABRICS

Application filed August 8, 1927. Serial No. 211,504.

This invention relates to a process of and apparatus for subjecting a fabric to a bath either for boiling off or dyeing natural silk, or for dyeing or delustering artificial silk composed either of reconstituted cellulose or 5 of cellulose derivatives such as cellulose acetate or for treating or dyeing fabrics of other fibres or mixtures thereof.

An object of our invention is to provide 10 a process of and apparatus for suspending the above mentioned fabric in a modifying bath as above stated in such a manner as to avoid "string-marking" caused by the strain due to suspension of the fabric by strings. 15 Other objects of our invention will appear from the following detailed description.

It is a common practice to boil off natural 20 silk fabrics by the use of the method known as stringing. In this process the fabric to be treated is plaited or folded and strings are affixed to one selvedge of the fabric. The fabric is then suspended on sticks by 25 means of the strings attached to the selvedge, so that it hangs in a plaited or folded condition, in a large rectangular tub containing the treating bath. This mode of treatment puts a strain upon the fabric where the string is attached to the selvedge due to the weight of the fabric being 30 supported, which weight is being carried by the points of support. The defect caused by this strain is commonly known as "string-marking". This "string marking" is not 35 noticeable with all fabrics, but certain fabrics, such as sheer natural crêpe-de-Chine and cellulose acetate fabrics, particularly where delustering is required, are very subject to this objectionable phenomenon.

We have found that in treating any 40 fabrics which are liable to "string mark", this defect can be avoided by the use of a clip or clamp to suspend the fabric, thus distributing all the weight of the fabric over a substantial portion of the selvedge instead of 45 at one point.

Referring to the accompanying drawing—

Fig. 1 is a plan view of the treating bath showing the fabrics suspended, the distances between the folds being exaggerated 50 for clarity.

Fig. 2 is a cross-section along line 2—2 in the direction of the arrows.

Fig. 3 is a side view of one form of clip with parts broken away to show the guiding pin. 55

Fig. 4 is a cross-section along the line 4—4 of Figure 3 in the direction of the arrows.

Fig. 5 is a side view of another form of clip. 60

Fig. 6 is an end view of the clip shown in Figure 5. 65

Fig. 7 is an end view of still another form of clip having a baffle for guiding the fabric.

Referring more particularly to Figures 1 and 2, the numeral 1 represents the tub here shown as rectangular, for containing the treating bath. The fabric 2 to be treated is folded or plaited along the fold 3 and is supported by the clips or clamps 4 along one selvedge, which in turn suspend from the rods or sticks 5 which rigidly support the clips 4. Almost any type of clip or clamp could be used, the wider the clip the more efficient it is for this purpose. A clip 3 inches to 6 inches wide has been found satisfactory, this taking the weight of the fabric over a 3 inch to 6 inch stretch of selvedge instead of at one point when a string is used. It has been found satisfactory to use three clips 80 across the fold of the fabric, one at each end of the fold and one in the center. The number of folds put in each set of three clips may be varied in accordance with the type or quantity of the fabric to be treated. Each set of 85 three clips are supported on a stick or rod so as to be held as rigidly as possible. Two, three or more clips may be used to a stick, just as two, three or more strings are supported by a stick in the old process. We 90 have found it desirable to have the clips fixed firmly to the supporting sticks so as not to allow lateral motion. 95

Referring more particularly to Figures 3 to 7, which show in detail the preferred forms of clips to be used in our invention, the reference numeral 6 indicates the jaws of the clips, which jaws are kept in the closed position by the spring 7. The clips or clamps are provided with the usual handles 8 for spreading 100

the jaws of the clips apart and for suspending the same. In the form of clips shown in Figures 3 to 6 the pins 9 are provided to guide the folds of the fabric into the clips, since difficulty was experienced in loading the folds of the fabric into the ordinary form of the clip. We have found that such fabric can be loaded very readily when these pins are provided. Attention is called to the fact that 10 the pins are so placed, that they do not support the fabric when the clip is closed but merely act as guides.

In the form of clip shown in Figures 3 and 15 4 the pins 9 project within the space between the jaws. In the form shown in Figures 5 and 6, the ends of the edges of one of the jaws are upturned as shown at 10 to provide space for the pin 9.

Referring to Figure 7, baffle 10 is provided 20 on one jaw 6 of the clip to guide the fabric into the space between the jaws.

The apparatus described above may be used in the process of boiling off natural silk. It may be used for dyeing fabrics such as natural silk crêpe-de-Chine and certain varieties 25 of artificial silk, particularly those made of organic cellulose derivatives such as cellulose ethers and cellulose acetate. It is particularly advantageous for delustering cellulose acetate fabrics. It is to be understood of course that the tub is filled with an appropriate liquid or solution necessary to carry out any of the above operations.

Having described our invention what we 30 claim and desire to secure by Letters Patent is:—

1. Apparatus for treating fabric liable to "string-marks" comprising a vessel adapted to serve as a support, bars extending across 40 said vessel and supported by it, means on said bars for suspending the fabric by a support for a substantial length of the fabric.

2. Apparatus for treating fabric liable to "string-marks" comprising a vessel adapted 45 to serve as a support, bars extending across said vessel and supported by it, a clip or clamp of substantial length for suspending the fabric by supporting the fabric along a substantial portion of its length, and means across the bath for supporting said clip or clamp.

3. Apparatus for treating fabric liable to "string-marks" comprising a vessel adapted to act as a support and means for suspending 55 the fabric, said means comprising a clip or clamp of substantial length for supporting the fabric along a substantial portion of its length, and a bar across the vessel and supported by it for supporting said clip or clamp.

4. Apparatus for treating fabric liable to "string-marks" comprising a vessel adapted 65 to act as a support and means for suspending the fabric, said means comprising a bar supported by said vessel and a depending clip or

clamp of substantial length, for supporting the fabric along substantial portions of its length, said clip or clamp having means on one of its jaws for aiding the positioning of the fabric into the same. 70

5. Apparatus for treating fabric liable to "string-marks" comprising a vessel adapted to act as a support and means for suspending the fabric, said means comprising a bar supported by said vessel and a depending clip or 75 clamp of substantial length for supporting the fabric along substantial portions of its length, said clip or clamp having pins on one of its jaws for aiding the positioning of the fabric into the same. 80

6. A clip or clamp for fabrics, comprising a pair of smooth faced gripping jaws for supporting the fabric, and means on one of said jaws for aiding the positioning of the fabric between the jaws, said jaws being 85 adapted when closed to receive the whole weight of the fabric independently of said positioning means.

7. A clip or clamp for fabrics, comprising a pair of smooth faced gripping jaws for 90 supporting the fabric, and a pin on one of said jaws for aiding the positioning of the fabric between the jaws, said jaws being adapted to relieve the said pin entirely of the weight of the fabric. 95

In testimony whereof, they have hereunto subscribed their names.

HERBERT PLATT.
